ELECTRONIC COMPRESSOR CONTROL

Walter S. Thompson, Los Angeles, Calif., assignor
to Radio Corporation of America, a corpora-
tion of Delaware

Application March 24, 1942, Serial No. 436,005

11 Claims. (Cl. 178—44)

This invention relates to electrical transmission systems, and particularly to an electrical compression system for sound recording, radio broadcasting or public address systems.

It is well known that electrical currents are compressed for various reasons, compression being used in the recording of sound for motion pictures to increase the film volume range, to aid the mixer and for various other reasons well known in the art. Thus, the use of compressors in sound recording channels is practically standard practice, one such compressor system being disclosed and claimed in U. S. Patent 2,255,683 of September 9, 1941 to Kurt Singer.

In the operation of such a compressor unit, the signal must first pass through a variable gain amplifier, one or more linear amplifiers, and a rectifier, before reaching the grids of the variable gain amplifier tubes at which point compression actually takes place. To obtain the necessary filtering between the rectifier and the grids of the variable gain amplifier tubes, it is necessary to use various circuit elements such as resistances and capacitances, and sometimes inductances, any of which introduce a delay in the compression action. If this filter delay is too short, there is a tendency for the system to oscillate.

Thus, compressors of the type above-mentioned have a delayed action, the result of which is to permit the beginning of certain signals to pass through the channel and be recorded or reproduced without compression. This introduces a distortion into the transmitted signal which is quite disagreeable, as it has a tendency to emphasize the first syllables of words.

The present invention is directed to a system for insuring compression action at all times, and particularly to the first few cycles at the beginning of any sound wave. This is accomplished in general by employing in the sound recording channel an instantaneous limiter which operates immediately upon the first cycle or cycles of any sound wave being transmitted therethrough having an amplitude within the compression range. During the period of operation of the instantaneous limiter the compressor becomes effective, the compressor then functioning in its normal manner. During this period when the compressor is becoming effective, it is simultaneously eliminating the action of the instantaneous limiter. Although the effect of the limiter is to flatten the tops of the first cycle or cycles of the waves, this distortion is not deleterious in com-

parison with that obtained when these cycles are not compressed.

The principal object of the invention, therefore, is to facilitate and improve the compression of electrical currents.

Another object of the invention is to insure compression action over the entire portion of a signal at which compression is desired.

10 Another object of the invention is to provide a compression transmission channel having an instantaneous limiter thereon for introducing compression during the inoperative period of the compressor.

15 A further object of the invention is to provide a combination compressor and instantaneous limiter in a transmission circuit, the instantaneous limiter being under control of the compressor, during the functioning of the compressor.

20 Although the novel features which are believed to be characteristic of this invention are pointed out with particularity in the claims appended herewith, the manner of its organization and the mode of its operation will be better understood by referring to the following description read in conjunction with the accompanying drawings, forming a part hereof, in which:

Fig. 1 is a block diagram of a sound recording channel embodying the invention;

25 Fig. 2 is a schematic circuit diagram of the compressor and instantaneous limiter used in the system of Fig. 1;

Fig. 3 is a graph showing the operation of one of the instantaneous limiter tubes;

30 Fig. 4 is a graph of a sine wave, illustrating the action of the compressor and instantaneous limiter thereon; and,

Fig. 5 and 6 are graphs showing the timing of the compressor and instantaneous limiter.

35 Referring now to Fig. 1, a microphone 5, or other source of signal currents, feeds a preamplifier 6, which is connected to a mixer 7 feeding a second amplifier 8. The amplifier 8 is connected to a compressor 9 of the type referred to in the above mentioned Singer patent, the output of the compressor feeding an instantaneous limiter 10 which is connected to a recorder amplifier 12 feeding a recorder 13. Bridged across the output of the limiter 10 is an isolation amplifier 15 feeding a monitoring speaker 16. The above system is a standard type of sound recording channel with the exception of the limiter 10, although this type of transmission channel may also be used in radio broadcasting or public address systems.

40 Referring now to Fig. 2, it will be observed that

the compressor unit is of the type shown in the above-mentioned Singer Patent 2,255,683 and will, therefore, not be described in detail. In operation, a signal is impressed over audio transformer 20 to variable gain tubes 21 and 22, the output of which is fed to a linear push-pull amplifier having tubes 24 and 25. A portion of the output of the tubes 24 and 25 is fed over conductors 28 and 29 to an amplifier 26 and then to a rectifier 27, the rectified current controlling the gain of tubes 21 and 22, as described in detail in the Singer patent. In the operation of the compressor, the breakaway point or point at which compression begins is determined by the potentiometer 30 while the date at which compression occurs is determined by the potentiometer 31.

As mentioned above, it requires a certain amount of time for the compression action to become effective, and this is true even when the amplifier 26 is connected to the input of the variable gain amplifier 21-22. To illustrate what occurs to a signal in such a compressor, reference is made to Fig. 4, wherein a sine wave of different amplitudes is shown. In this illustration, the breakaway or compression point has been set at a level corresponding to the peaks of the first cycle *a*. Thus, with the normal compressor, the first cycle *b*-*c*, of greater amplitude than cycle *a*, will pass to the recorder without compression, while the succeeding cycle *d* will receive compression as shown by the full line curve. Since the time period in which it takes the compressor to become fully effective is substantially constant, the number of peaks of any particular wave which will pass through uncomplicated will depend, of course, on the frequency of the wave. As will be shown hereinafter, the present invention compresses all peaks above the pre-determined compression point.

Referring again to Fig. 2, it will be noted that the output transformer 33 feeds a pair of push-pull amplifier tubes 34 and 35 having resistors 36 and 37 in their grid circuits. In the common grid conductor for these tubes there is a fixed bias potential provided by a battery 39 or other suitable source in series with a resistor 40. The point 41 on the common grid return for the tubes 34 and 35 is connected by a conductor 42 to the rectifier 27 at point 43. By this connection, the instantaneous gain of the tubes 34 and 35 is controlled simultaneously with the control of the normal gain of tubes 21 and 22 by the output of the rectifier 27.

To explain what occurs to the wave of Fig. 4, in its transmission through limiter tubes 34 and 35, reference is made to Fig. 3 showing a grid voltage-plate current characteristic of one of the tubes 34 and 35. It will be noted that the shoulder of the characteristic curve has a sharp break at point A which provides a limiting action at substantially zero grid potential. By adjustment of the biasing battery 39 and the potentiometer 30, the operating point for the tubes 34 and 35 is placed at point B. Thus, the first cycle *a* of the signal of Fig. 4 will be transmitted through the tubes 34 and 35 without compression or distortion as shown by the sine waves *a'* and *a''* in Fig. 3. However, when the cycle *b*-*c* of Fig. 4 is impressed on the tubes 34 and 35, the result is shown at *b''*-*c'*, which result is the flattening of the half-cycle *b*' as shown at *b*'. Although only the half-cycle *b*' is shown flattened in Fig. 3, it is realized of course, that the half-cycle *c*' will receive the same flattening action in the other

tube, since the two tubes are functioning in a push-pull relationship. Thus, the complete cycle *b*'-*c*' will be flattened and compressed. Although it is realized that the flattening of the peaks of cycle *b*'-*c*' does not exactly correspond to the compression action as shown by the dot and dash lines in cycle *b*-*c* of Fig. 4, and thus introduces distortion, it has been found that this type of distortion is negligible in comparison to that produced when the first few cycles of a word are transmitted without any compression at all.

The effect of this flattening of the peaks is shown in Fig. 4, by the dotted lines within the cycle *b*-*c*. This type of compression is not, of course, desirable for the entire signal, and it is, therefore, necessary that the normal type of compressor action be substituted to retain the original wave form of the wave. However, by the time the cycle *b*-*c* has been transmitted through tubes 34 and 35, the compressor has become effective and normal compression for the succeeding cycle will occur, as shown in Fig. 4 by the full line cycle *d*. During the time period that compression tubes 21 and 22 are becoming effective, 20 the bias on limiter tubes 34 and 35 is being changed over conductor 42 to move the operation point for these tubes down to point C. This action is shown in Figs. 5 and 6, wherein the horizontal portions *e* and *e'* of the curves may 25 represent the time that cycle *a* is being transmitted, while the sloped portions *f* and *f'* of the curves in a horizontal direction, represent the time cycle *b*-*c* is being transmitted. Thus, with the time period *f* made equal to the period *f'*, 30 the limiter action is eliminated during the same time interval that is required for the compressor to become effective. Furthermore, by selecting the proper values of grid bias 39 and resistors 36 and 37 with respect to the operating characteristics of tubes 21 and 22, the same rate of change 35 may be obtained in the compressor and limiter, but in an opposite sense as shown by the slopes of portions *f* and *f'*. Thus the amount of flattening is made comparable to the amount of compression 40 (see Fig. 4).

It will be noted that tubes 21 and 22 and tubes 34 and 35 linearly amplify all signals having amplitudes below the compression point, but when greater amplitudes are transmitted, the effective 45 gain of tubes 34 and 35 instantaneously drops to a point corresponding to the eventual gain of the compressor. However, the rectifier output caused by cycle *b*-*c* immediately begins to vary the gain of the compressor tubes and simultaneously shift the instantaneous gain of the limiter tubes at the same rate but in an opposite sense, so that when cycle *d* reaches the compressor, compressing action is fully effective and tubes 34 and 35, operating about point C, linearly amplify or transmit 50 without amplification, all signal levels.

It will be observed from the above combination of compressor and instantaneous limiter, that the compressor can now be provided with all filtering necessary between the rectifier and grids of the variable gain amplifier tubes, since the instantaneous limiter will provide any time interval desired. Although the limiter has been shown controlled by the compressor, it is to be understood that it may be self-controlled or controlled 55 by a rectifier separate from the compressor rectifier so that the limiter may be rendered ineffective over a time interval different from that of the compressor.

What I claim as my invention is:

1. In an electrical transmission system, the

combination of means for generating electrical currents, means for compressing the amplitudes of said currents in a predetermined amount, said compressing means having a delayed action which permits the beginning of said currents to be transmitted therethrough without compression, a second means for compressing the beginning of said currents during the inoperative period of said compressing means, and means for simultaneously controlling both of said compressing means, said last mentioned means making said first compressing means operative while making said second compressing means inoperative over the same time periods.

2. An electrical transmission system in accordance with claim 1, in which said first mentioned compressing means renders ineffective said second compressing means when said first compressing means is effective.

3. An electrical transmission system in accordance with claim 1 in which said second compressing means comprises a current limiter under control of said compressing means.

4. An electrical compressing system comprising a compressor unit for signals transmitted therethrough, a rectifier included in said compressor unit for rectifying said signals to obtain a biasing current for said compressor unit, and a current limiter connected to the output circuit of said compressor unit for transmitting said signals and to the output circuit of said rectifier, for transmitting said rectifier currents to said limiter for biasing said limiter to a non-limiting condition while said compressor is being biased to a compressing condition.

5. The method of compressing a predetermined signal range of amplitudes with a compressor circuit requiring a certain time period for the signal to introduce a predetermined amount of compression into said signal, comprising instantaneously limiting the transmitted amplitudes of said range externally of said compressor circuit and varying the effectiveness of said limiting action during said certain period required for said compression action to become effective, said limiting action being totally ineffective when said signal has introduced said predetermined amount of compression into said signal.

6. The method in accordance with claim 5 in which the limiting action is decreased at the same rate and over the same time period required for said compressing action to become effective.

7. In combination, a signal transmission line, a delayed action amplitude limiting device in said line for limiting the amplitude of transmitted signals according to a predetermined ratio, a second instantaneous amplitude limiting device for limiting the amplitude of the portion of said signals not limited by said first device, and means acting on said devices for simul-

taneously eliminating the limiting ability of said second device while making effective the limiting ability of said first device.

8. In combination, a signal transmission line, a compressor including a variable gain amplifier, a rectifier, means for connecting the output of said variable gain amplifier to the input of said rectifier, means for connecting the output of said rectifier to the gain control electrodes of said variable gain amplifier, the above mentioned elements forming a compressor unit, a limiting amplifier connected to the output of said variable gain amplifier, and means for connecting the output of said rectifier to the input of said limiting amplifier, the output of said rectifier introducing compression action in said variable gain amplifier as said limiting amplifier is made non-limiting.

9. In combination, an incoming transmission line, an outgoing transmission line, a variable gain amplifier having gain control electrodes and a limiting amplifier having gain control electrodes, said amplifier being connected in series between said incoming line and said outgoing line, a rectifier for rectifying a portion of the signal being transmitted, means for impressing the output of said rectifier on the gain control electrodes of both said variable gain amplifier and said limiting amplifier, the output of said rectifier causing said variable gain amplifier to compress the signal transmitted therethrough and said limiting amplifier to become ineffective to limit said signal.

10. In a system for reducing the amplitude of signals, in a predetermined ratio, the combination of a variable gain amplifier, a rectifier for producing a current substantially proportional to the average amplitude of said signals, means for connecting the output of said rectifier with the gain control elements of said variable gain amplifier, a second limiting amplifier for said signals connected to the output of said variable gain amplifier, and means for connecting the output of said rectifier to the control electrodes of both of said amplifiers, said second amplifier reducing the amplitude of said signals from a maximum to a minimum amount as said variable gain amplifier reduces the amplitude of said signals from a minimum to a maximum amount over a predetermined initial time period.

11. An electrical current transmission system comprising a source of electrical currents, a delayed action compressor unit for said currents, an instantaneously acting limiting device for said current, and means for interconnecting said unit and device for compressing said currents with substantially no distortion, said limiting device being made inoperative as said compressor unit becomes operative.

60 WALTER S. THOMPSON.
